UNITED STATES PATENT OFFICE.

PETER H. BRODESSER, OF MILWAUKEE, WISCONSIN.

ELECTRIC ELEVATOR.

Application filed June 2, 1922. Serial No. 565,416.

This invention relates to elevators and is particularly directed to a system of control for electric elevators.

Objects of this invention are to provide a system for controlling elevators by which the elevator may be accurately stopped in correct alignment at the desired floor; to provide such a system in which the elevator is slowed down as it approaches the floor and is automatically stopped at the exact floor level; and to provide such a system in which manual and automatic control of the elevator are combined to secure the above enumerated results.

Further objects are to provide a system of control for electric elevators in which a small motor and a large motor are provided, which are respectively connected with a winding drum by a large and relatively smaller reduction gearing; in which the smaller motor is used through its large reduction gearing to slowly start the load and give it a certain predetermined speed, and thereafter to allow the larger motor to take the load and further accelerate it; and to provide such a system in which the use of standard equipment in its major part is permitted.

Further objects are to provide a system for the control of electric elevators in which a relatively small starting current is used, thereby avoiding the overloading of the motors on the one hand and the excessive line current at starting on the other; to provide such a system in which the usual large losses in the control resistances are avoided, and in which each of the motors is kept, during a large part of the time, working at its most efficient speed.

Further objects are to provide a system for automatically aligning the car with the particular floor at which it is desired to stop; to secure such automatic alignment independently of any stretch or elongation that may occur in the cables associated with the counterweight.

Further objects are to provide a system of two-motor elevator operation for securing accurate alignment of the elevator with the floor, in which a stationary brake is employed, that is to say, an electromagnetic brake which is not called upon to rotate but which is at all times relatively stationary to thereby secure all of the protection afforded by stationary brakes while allow-

ing the accurate and flexible control necessary for the proper alignment of the elevator with the floor.

Further objects are to provide a system in which the brake is so associated with the two motors that it is released when either motor operates; in which automatic electromagnetic means are provided for shifting the load from one motor to the other; in which the auxiliary motor, together with its drive and the brake, jointly and independently, sustain the load when such load is at rest.

Further objects are to provide a multiple speed control for alternating current systems for electric elevator drive; in which the speed control of the alternating current motors is so secured that the usual type of alternating current motor may be employed; and to provide such a system, in which, although alternating current motors of the usual construction are utilized, it is still possible to secure accurate speed control and accurate floor alignment.

Embodiments of the invention are shown in the accompanying drawings, in which:

Fig. 1 is a diagrammatic view showing a system for electric elevator control in which alternating current motors are employed.

Fig. 2 is a similar system in which direct current motors are employed.

Fig. 3 is an elevation, partly in section, of the motors with the automatic devices associated therewith, showing a convenient association of such devices.

Fig. 4 is a plan view of the structure shown in Fig. 3.

Fig. 5 is a fragmentary elevation of a portion of the apparatus for automatically aligning the elevator at the particular floor at which it is desired to stop.

Fig. 1, showing one form of the invention, will first be described. In this figure, a system for controlling electric elevators is disclosed in which a relatively large main motor indicated generally at 1 and a relatively small or auxiliary motor indicated generally at 2 are provided. The large motor has its armature 3 directly and permanently connected to a shaft 4 which, by means of the worm 5 and worm wheel 6, drives the winding drum 7. The auxiliary motor has the armature 8 connected by means of a worm 9 with a worm wheel 10.

loosely mounted upon the shaft 4. A friction clutch 11 is adapted to couple this loosely mounted worm operatively to the shaft 4, under certain predetermined conditions, as follows: either when the auxiliary motor is driving, or when the entire system is still, that is to say, when there is no current flowing in the circuits. The clutch is released by means of an electro-
 10 magnetic device, comprising a solenoid 12, a plunger 13, and lever 14, whenever current flows in the stator windings of the main motor 1. A stationary brake, indicated generally at 15, is provided upon the
 15 shaft 4, the disk 16 of which is permanently connected to such shaft, the brake band 17 being forced apart by any suitable mechanism operated from the plunger 18 of the solenoid 19. The system is so
 20 designed that when current flows through the stator windings of either the auxiliary or main motor the brake will release.
 A manually operable controller is provided and is preferably located upon the
 25 elevator car in the usual manner. It comprises a lever 20 pivoted at 21 and provided with an operating handle 22. Upon the upper side of the lever, a plurality of contacts 23, 24 and 25 are provided and are
 30 connected by means of the conductors 26, 27 and 28 with the mains 29, 30 and 31. The stationary contacts of the controller cooperating with the movable contacts just described comprise four series of contacts,
 35 one set 32, 33 and 34 being connected with the stator windings of the auxiliary motor by means of conductors 35, 36 and 37. It is to be noted, however, that the conductor 35 does not lead directly to one of the taps
 40 of the stator winding of the auxiliary motor, but by means of the conductor 38 leads through the solenoid 19 of the electromagnetic brake and from thence by means of conductor 39 to the appropriate tap on the
 45 stator winding of the auxiliary motor. A similar series of contacts is provided upon the opposite side of the controller with, however, the single exception that two of the taps leading to the stator winding are
 50 reversed so as to give a reverse direction of rotation of the polyphase auxiliary motor, it, of course, being understood that the mains 29, 30 and 31 supply three-phase current to the system.
 55 The next series of contacts 40, 41 and 42 lead by means of conductors 43, 44 and 45 to the stator windings of the main motor. However, the conductor 44 does not lead directly to the stator windings of the main motor, but leads to the solenoid 46 of an electromagnetic contactor and from thence by means of the conductor 47 to its appropriate tap on the main motor stator winding. In a similar manner, the conductor 43
 60 65 leads through the solenoid 19 of the elec-

tromagnetic brake, and from thence by means of the conductor 48 to its appropriate tap on the stator winding of the main motor. The corresponding set of contacts upon the opposite side of the controller are
 70 connected in the same manner except that two of the taps of the stator windings are reversed so as to give a reverse direction of rotation of the main motor.

From the construction thus far given, it will be seen that when the auxiliary motor is energized, the solenoid 19 of the electromagnetic brake is energized and the brake is released. It will also be seen that when the main motor is energized both the electromagnetic brake solenoid 19 and the contactor solenoid 46 are energized.

The contactor comprises the solenoid 46, previously described, a plunger 49, and movable contact 50. This movable contact is carried by the plunger and insulated therefrom, and is adapted to connect the two stationary contacts 51 and 52, thereby closing an auxiliary circuit from the mains 30 and 31 through the solenoid 12 of the electromagnetic friction brake, through the medium of the conductors 53 and 54.

Upon the lower end of the controller lever 20, a plurality of contacts 55, 56 and 57 are provided, and are connected with the mains 29, 30 and 31, respectively. It is to be noted, however, that these contacts are not connected directly to the mains, but through the medium of switch blades 58. These switch blades form a part of an automatic cutout device, and one connected together by means of an operating plunger 59 which extends outwardly from a housing 60, see Fig. 5, and is operated by a lever 61. This lever 61 is pivoted at 62 and is pressed outwardly by means of a spring 63. At its free end, it carries a roller 64 which is adapted to be actuated by means of a cam 65 secured to some portion of the hatchway, or runway, of the counterweight 66. It is to be noted that this cam has a gradual approach on each side and a central peak 67. When the roller 64 arrives at the central peak 67, the switches 58 are opened and the auxiliary circuit controlled thereby is correspondingly opened.

The stationary contacts corresponding to the last described movable contacts are indicated at 68, 69 and 70 and are connected to the conductors 35, 37 and 36 respectively. It will be seen, therefore, that when the controller is moved to the first point to the right that the auxiliary circuit established by the contacts 55, 56 and 57 and the cooperating contacts 68, 69 and 70 is identical to that established by the stationary contacts 32, 33 and 34 and the corresponding movable contacts when the controller is moved to its second position to the right.

However, this auxiliary circuit includes the automatic switches and, it will be seen, is open when the car exactly aligns with a floor.

- 5 The operation of the system is as follows: When it is desired to start the car, the controller is moved to the second point and the auxiliary motor is connected directly to the mains. It speeds the car up to a 70 predetermined relatively low speed and, it will be seen, rotates the armature 3 of the main motor. When the controller is moved to the second point, the main motor is then energized and the auxiliary motor deenergized. 75 10 The main motor having been brought up to a certain speed immediately picks up and assumes the load without any excessive line current, or loading, resulting. It is to be noted that when either 15 motor is energized, the brake is released and when the main motor is energized, the contactor blade 50 completes the auxiliary circuit through the electromagnetic control of the friction clutch, thereby opening such 20 clutch and mechanically disconnecting the auxiliary motor from the hoisting mechanism.

When it is desired to stop at a given 25 floor, the controller is moved to the first position. In this position, the auxiliary circuit of the auxiliary motor is established and such motor drives the car at a reduced rate of speed towards the floor landing. At the time the car exactly aligns with the 30 floor, the automatic switches function and cut out the auxiliary motor as previously described.

Fig. 2 shows a further modified form of 35 the invention and shows a system adapted for direct current. The same arrangement of hoisting mechanism, brake, friction clutch, and contactor is employed in this system as in that previously described. The main motor armature is indicated at 40 45 71 and its field at 72. The auxiliary motor armature is indicated at 73 and its field at 74. The contactor solenoid is indicated at 75. The same reference characters 50, 51 and 52 indicate the movable and stationary contacts of this contactor.

The controller lever 76 is similarly pivoted adjacent its approximate central portion as indicated at 77 and is provided with an operating handle 78. Its upper portion carries four movable contacts 79, 80, 81 and 82, the contacts 80 and 82 being connected by means of conductors 83 with one of the mains 84. The uppermost contacts 79 is connected to one of the brushes 80 of the armature 71 of the main motor by means of the conductor 85. The contact 81 is connected by means of conductors 86 and 87 with one of the brushes 88 of the auxiliary motor. The other brush 89 of the main motor is connected through the scribed. It is also to be noted that the fric-

solenoid 75 of the contactor and through the solenoid 19 of the electromagnetic brake and to the main 90 by means of conductors 91, 92 and 93. The second brush 94 of the auxiliary motor is similarly connected with the main 90 but its circuit does not pass through the contactor solenoid 75 but only through the brake solenoid 19. An auxiliary circuit for the solenoid 12 of the friction clutch is provided by means of conductors 94 and 95 and is controlled by the contacts 50, 51 and 52 of the contactor in a manner similar to that previously described.

When the controller lever is moved to the second point to the right, it connects the brush 88 of the auxiliary motor to the elongated contact 96. From thence the circuit passes by means of conductors 97 and 98 to one side of the field 74 of the auxiliary 80 85 motor. The other side of the field is connected by means of conductors 99 and 100 to a contact 101 and from thence through a resistance 102 to the other second point position contact 103. This contact is connected, when the controller is in the position described, that is to say, second point right, with the main 84 by means of conductor 83. It will be seen, therefore, that the armature and field of the auxiliary 90 95 motor are connected in series with the resistance 102 and with the solenoid 19 of the brake. The auxiliary motor, therefore, runs at a relatively low speed and slowly starts the car and hoisting mechanism and rotates the armature 71 of the main motor.

When the controller is moved to the next point, the resistance 102 is cut out and the auxiliary motor runs at its full speed. When the controller is moved to the next 100 105 position to the right, the contact 79 engages the elongated contact 104 and connects the brush 80 of the main motor with its field 72 by means of conductors 105 and 106. The other side of the field 72 is connected by means of conductors 107 and 108 to contact 109 through a resistance 110 to contact 111. From this point, the circuit continues through conductor 83 to the main 110 115 84. The other brush 89 of the main motor is connected through the contactor solenoid 75 and the brake solenoid 19 with the main 90, as will be readily seen. It will be seen, therefore, that when the controller is in the last described position, the main motor is connected through the solenoids of the contactor and brake and through the resistance 110 with the mains. The elevating mechanism and car are consequently accelerated.

It is to be noted, however, that the armature of the main motor was already rotated at a fair rate of speed before the main motor was energized, thereby cutting down the starting current as previously described. It is also to be noted that the fric-

tion brake is opened or released as its auxiliary circuit has been closed by the contactor.

When the controller is moved to its last point to the right, all of the resistance is cut out of the main motor circuit and the elevator is driven at its maximum rate of speed.

The lower portion of the controller lever 10 carries a pair of movable contacts 112 and 113. These contacts are connected respectively with the brush 88 of the auxiliary motor through the medium of the conductor 87, and with the automatic cut out switch 15 114 through the medium of conductor 115. From the automatic switch, the last mentioned contact is connected with the main 84 by means of conductor 116. This switch is operated by means of the stem 59 in the 20 same manner as the automatic switches previously described. When the controller is moved to first position to the right, the contact 112 cooperates with the contact 117 and connects the brush 88 with one side of 25 the field 74. The other side of the field is connected to contact 119 and from thence to the main 84 after passing through the automatic switch 114. The other portions 30 of the auxiliary motor circuit are the same as that described for second and third point controller positions.

It will be seen, therefore, that when the controller is in its first position that the auxiliary motor is connected with the mains 35 and a resistance and the automatic switch 114 is placed in series in this circuit. The auxiliary motor, therefore, slowly drives the car towards the desired landing. When the car aligns with the landing, the automatic switch opens and the car is stopped 40 exactly in its correct position.

In order to secure the reverse direction of rotation, the opposite side of the controller is provided with corresponding contacts so 45 connected with the fields of the motors that the current in such fields is reversed relatively to the armatures. A similar organization of contacts at the lower portion of the controller is provided so that the correct 50 direction of rotation of the auxiliary motor, when under the control of the automatic switch, is assured.

In the form of the invention shown and 55 described, it has been contemplated associating an auxiliary member or cross head 120 with the counterweight 66 and suspending such cross head by means of a cable 121 so that the cross head position is independent of the stretch of the main supporting cables 60 122 of the counterweight. The housing 60 for the automatic switches is carried by this cross head as shown in Fig. 5 so that stretching of the cables will not affect the correct alignment of the car with the floor. However, it is to be understood that the auto- 65

matic switches may be carried directly by the car, if so desired, and that the cam may be positioned in the hatchway or, as an alternative construction, the cam may be carried by the car and automatic switches may 70 be placed in the hatchway.

It will be seen from the disclosure here- 75 with given that a combined automatic and manual control for electric elevators has been provided in which the car may be made to slowly approach the desired floor and when arriving in exact alignment with such floor, to be automatically stopped. If it is desired to travel past this floor while on reduced speed, it is merely necessary to move 80 the controller to its second point position. In this position, the automatic switches are bridged and the auxiliary motor continues to operate, although the automatic switches will open as the floor is passed. 85

It will further be seen that a system of 90 control for electric elevators has been provided in which both of the two motors are so associated with the hoisting mechanism and electrical circuits, that either motor may continuously operate, if desired, at its most efficient speed. It will further be seen, that in the normal operation of the elevator, very little energy is wasted in the resistance as a large part of the control is secured by 95 changing motors.

I claim:

1. In a control system for electric elevators, the combination of a hoisting apparatus, a main motor and an auxiliary 100 motor, mechanism for connecting said motors to said hoisting apparatus, a manually operable controller for starting the elevator by said auxiliary motor and for thereafter accelerating said elevator by said main motor, an automatic device including switches actuated when the elevator arrives at a floor landing to open such switches, and means carried by said controller for electrically connecting said auxiliary motor with said switches when said controller occupies a pre-determined position, whereby said elevator may be run past any floor landing when driven either by said main or auxiliary motor, or may be automatically stopped at said 110 floor landing when driven by said auxiliary motor. 115

2. A system of control for electric elevators having a hoisting drum and a stationary 120 brake, said system comprising a main motor directly mechanically connected to said hoisting drum, an auxiliary motor adapted for intermittent connection to said hoisting drum through a reduction gearing, electromagnetic means for operatively connecting said auxiliary motor and said hoisting drum under predetermined conditions, other electromagnetic means controlled by the current supplied said main motor to control the 125 actuation of said first mentioned electro- 130

- 5 magnetic means, a manually operable controller for selectively connecting either said main motor or said auxiliary motor to a source of electric supply, and for connecting 5 said auxiliary motor through a secondary circuit to said source of electric supply, and an automatic device for interrupting said secondary circuit as the elevator arrives at each floor landing.
- 10 3. A system of control for electric elevators comprising a hoisting mechanism, a main and an auxiliary motor operatively connected thereto to drive the hoisting mechanism at different speeds, manual means 15 for selectively connecting either of said motors to a source of electrical energy, a normally closed automatic switch controlling the circuit of the auxiliary motor, a movable switch actuating member associated with 20 the travelling portions of the hoisting mechanism and adapted, when moved in one direction, to open said automatic switch, co-operating and relatively stationary members adapted to engage and actuate said movable 25 switch actuating member in said direction at predetermined points in its line of travel between its initial and final positions, said switch being normally closed and adapted to be automatically opened by said relatively stationary members, whereby said mechanism may be automatically stopped at certain points in its line of travel when propelled by the auxiliary motor.
4. A system of control for electric elevators comprising a hoisting mechanism including a load lifting platform, a series of landing stations, a main motor mechanically connected to the hoisting mechanism, an auxiliary motor normally mechanically connected to said hoisting mechanism, electromagnetic means for interrupting the operative connection between said auxiliary motor and said hoisting mechanism, a contactor responsive to energization of said main motor for controlling said electromagnetic means, manual means for separately connecting either of said motors with a source of electrical energy, and automatic means normally operative whenever the hoisting platform reaches a landing station for disconnecting said auxiliary motor from said source of electrical energy, said motors being otherwise subject to separate manual control.
- 55 5. A system of control for electric elevators comprising hoisting mechanism including a load lifting platform, a series of landing stations, a main motor and an auxiliary motor each operatively connected to the hoisting mechanism to operate the latter at different speeds, manual means for selectively connecting either of said motors to a source of electrical energy, and automatic means for normally causing the deenergization of said auxiliary motor whenever the load lifting platform reaches a landing station, said manual means being the sole instrumentality for permitting the energization of said auxiliary motor.
6. A system of control for electric elevators comprising the combination of a hoisting drum, a main motor operatively connected thereto, an auxiliary motor having an automatically acting releasable mechanical connection with said hoisting drum, electromagnetic means for releasing said connection, a contactor electrically controlling said electromagnetic means and provided with an operating coil in series with the main motor circuit, and a manually operable device adapted to alternatively connect up the circuits of the main and auxiliary motors, whereby the mechanical connection and disconnection of the auxiliary motor is made dependent upon the circuit of the main motor.
7. A system of control for electric elevators comprising the combination of a hoisting mechanism, a main motor permanently connected therewith, an auxiliary motor, means for normally coupling said auxiliary motor to said hoisting mechanism, electromagnetic means controlled by the main motor circuit for releasing the coupling while the circuit of the main motor is closed, a manually operable device adapted to alternatively connect up the circuits of the main and auxiliary motors, said coupling being adapted to mechanically connect the auxiliary motor with the hoisting mechanism whenever the circuit of the main motor is open independently of the electrical connections of the auxiliary motor.
8. A system of control for electric elevators comprising the combination of hoisting mechanism, a main motor permanently connected therewith, an auxiliary motor having a detachable mechanical connection with the hoisting mechanism, means controlled by the main motor circuit for mechanically disconnecting the auxiliary motor from said hoisting mechanism while the main motor is in operation, a manually operable device adapted in either of two positions to connect up the circuit of the auxiliary motor and in a third position to connect up the circuit of the main motor, and an automatic circuit breaker controlled as to operation by the hoisting mechanism and adapted to automatically open the circuit of the auxiliary motor at a predetermined stage in the operation of the hoisting mechanism when the lever is in one of its two first mentioned circuit closing positions.
9. A system of control for electric elevators comprising the combination of a hoisting mechanism including a load lifting member, a series of landing stations along the path of said load lifting member, a

main motor operatively connected to the hoisting mechanism, an auxiliary motor, means for automatically coupling the auxiliary motor to said hoisting mechanism to operate the latter at reduced speed, electro-magnetic means for retracting the coupling when the circuit of the main motor is closed, a contactor having a controlling coil in series with the main motor and adapted to close an energizing circuit of the electro-magnetic means when the contactor coil is energized, a manually operable switch for alternatively connecting up the circuits of the main and auxiliary motors and automatic means subject to manual control, for opening the circuit of the auxiliary motor whenever said load lifting member reaches one of said landing stations.

10. A system of control for electric elevators comprising the combination of a hoisting mechanism, a main motor operatively connected thereto, an auxiliary motor, means for automatically coupling the auxiliary motor to said hoisting mechanism to operate the latter at reduced speed, electro-magnetic means for retracting the coupling when the circuit of the main motor is closed, a contactor having a controlling coil in series with the main motor and adapted to close an energizing circuit of the electro-magnetic means when the contactor coil is energized, and a manually operable switch for alternatively connecting up the circuits of the main and auxiliary motors, said manually operable switch being adjustable to a neutral position with both motor circuits open and the auxiliary motor coupled to the hoisting mechanism.

11. A system of control for electric elevators comprising the combination of a reciprocating carrier, main and auxiliary motors having connections adapted to transmit motion to the load carrier at different speeds, an independently acting mechanical brake having an electrically operated brake releasing device provided with an exciting coil in series with both motors, means for automatically releasing the motion transmitting connections of the auxiliary motor from the load carrier when the main motor is energized, and a manually operable switch adapted in one position to connect up a circuit of the main motor, in another position to connect up a circuit of the auxiliary motor, and in a third position to disconnect both motors and release said mechanical brake for operation in maintaining the position of the load carrier.

12. A system of control for electric elevators comprising the combination of a reciprocating load carrier, a main motor having a hoisting drum mounted upon its shaft, an auxiliary motor having associated reduction gears, an automatically acting clutch for operating the shaft and drum at

reduced speed, electrically operated clutch releasing devices controlled by the circuit of the main motor, and a manually operable switch adapted to alternatively close and open the circuits of the respective motors and also adapted in one position of adjustment to open the circuits of both motors and simultaneously release said clutch to connect the auxiliary motor with the shaft and drum.

13. A system of control for electric elevators comprising the combination of a reciprocating load carrier, a main motor having a hoisting drum mounted upon its shaft, an auxiliary motor having associated reduction gears, an automatically acting clutch for operating the shaft and drum at reduced speed, electrically operated clutch releasing devices controlled by the circuit of the main motor, a manually operable switch adapted to alternatively close and open the circuits of the respective motors and also adapted in one position of adjustment to open the circuits of both motors and simultaneously release said clutch to connect the auxiliary motor with the shaft and drum, and means dependent upon the position of the load carrier for automatically opening the circuit of the auxiliary motor when the manually operable switch is in one position of adjustment, whereby the auxiliary motor may be rendered automatically inoperable when the load carrier reaches certain predetermined positions, the main motor being subject to continuous manual control in all positions of the load carrier.

14. A system of control for electric elevators comprising an elevator platform, means for reciprocating the platform, a main motor permanently connected thereto, an auxiliary motor, means for detachably connecting said auxiliary motor to said reciprocating mechanism, a manually operable device for connecting either of said motors to a source of electric energy independently of the other motor, said device having a neutral position with the circuits of both motors open, means for automatically breaking a circuit of the auxiliary motor when the elevator platform is in a certain predetermined position, means for adjusting the manually operable device to connect up a circuit of the auxiliary motor independent of said automatic circuit breaking means, while allowing the circuit of the main motor to be closed with the platform in such position, whereby said platform may, at the will of the operator, be actuated continuously by the main motor or to a predetermined stopping position by the auxiliary motor.

15. A system of control for electric elevators comprising the combination with an elevator platform and an operatively asso-

- ciated hoisting drum, of a main motor permanently connected with the hoisting drum, an auxiliary motor adapted to be detachably connected with the hoisting drum, a circuit breaker adapted to automatically open a circuit of the auxiliary motor when the platform is in predetermined positions of elevation, and a manually operable device adapted to alternatively connect up the
- 10 main and auxiliary motors with a source of electrical energy, said device being adapted in one position to close a circuit of the auxiliary motor **subject to the action of said circuit breaker and in another position to**
- 15 close an independent circuit of said auxiliary motor.
16. A system of control for electric elevators comprising the combination with an elevator platform and associated hoisting
- 20 mechanism, of a set of main and auxiliary motors for operating said platform, electrically controlled means for mechanically disconnecting the auxiliary motor from the hoisting mechanism when the main motor is
- 25 in operation, a circuit breaker for the auxiliary motor adapted for automatic oper-
- ation when the platform is in a predetermined position of elevation, and a manually operable device adapted to selectively connect up a circuit of the auxiliary motor subject to the action of the circuit breaker or to connect up circuit of either the auxiliary motor or main motor independently of the circuit breaker.
17. A system of control for electric elevators comprising the combination with hoisting mechanism, of main and auxiliary motors adapted to alternatively actuate said hoisting mechanism, a manually operable switch adapted in either of two positions to connect up a circuit of the auxiliary motor and in a third position to connect up a circuit of the main motor, and a circuit breaker adapted to automatically open one of the auxiliary motor circuits at predetermined stages in the operation of the hoisting mechanism, whereby said switch may be utilized to operate both of the motors independently of said circuit breaker or to operate said auxiliary motor subject to the action of said circuit breaker.

PETER H. BRODESSER.
